CLAIM

The ornamental design for a cutting tool, as shown and described.

DESCRIPTION

Cross reference is made to copending U.S. design patent application Ser. No. 29/571,645 entitled "Cutting Tool" by Arvind Gopi filed on even date herewith; U.S. design patent application Ser. No. 29/571,646 entitled "Cutting Tool" by Arvind Gopi filed on even date herewith; U.S. design patent application Ser. No. 29/571,647 entitled "Cutting Tool" by Arvind Gopi filed on even date herewith, and U.S. design patent application Ser. No. 29/571,651 entitled "Cutting Tool" by Arvind Gopi filed on even date herewith.

FIG. 1 is a perspective view of a cutting tool showing my new design;

FIG. 2 is a front elevational view showing the design for the cutting tool of FIG. 1;

FIG. 3 is a rear elevational view showing the design for the cutting tool of FIG. 1;

FIG. 4 is a right side elevational view showing the design for the cutting tool of FIG. 1;

FIG. 5 is a left side elevational view showing the design for the cutting tool of FIG. 1;

FIG. 6 is a top plan view showing the design for the cutting tool of FIG. 1; and,

(Continued)

FIG. 7 is a bottom plan view showing the design for the cutting tool of FIG. 1.

The broken lines shown in the figures illustrate portions of the cutting tool that form no part of the claimed design.

1 Claim, 5 Drawing Sheets
